BED SPRING SUPPORT

Ralph William Rosenthal, Jr., Toledo, Ohio, assignor to The Toledo Metal Bed Slat Company, Toledo, Ohio, a corporation of Ohio

Application September 6, 1951, Serial No. 16,527

Term of patent 14 years

(Cl. D5—2)

To all whom it may concern:

Be it known that I, Ralph William Rosenthal, Jr., a citizen of the United States and resident of Toledo, in the county of Lucas and State of Ohio, have invented a new, original, and ornamental Design for a Bed Spring Support, of which the following is a specification, reference being had to the accompanying drawing, forming a part thereof.

In the drawing, Fig. 1 is a perspective view of a bed spring support embodying my new design; Fig. 2 is a side elevational view thereof; Fig. 3 is an end view, and Fig. 4 is a top plan view thereof.

I claim:

The ornamental design for a bed spring support, substantially as shown.

RALPH WILLIAM ROSENTHAL, JR.
